UNITED STATES PATENT OFFICE

106,976

DESIGN FOR A COMBINED CAKE OF SOAP AND SUPPORT THEREFOR

Lynde De F. Hokerk, Utica, N. Y., assignor to
Kerk Guild, Inc., Whitesboro, N. Y., a corpora-
tion of New York

Application April 22, 1937, Serial No. 68,940

Term of patent 14 years

● *To all whom it may concern:*

Be it known that I, Lynde De F. Hokerk, a citizen of the United States, residing at Utica, in the county of Oneida and State of New York, have invented a new, original, and ornamental Design for a Combined Cake of Soap and Support Therefor, of which the following is a specification, reference being had to the accompanying drawing, forming part thereof.

In the drawing, the figure is a perspective view of the combined cake of soap and support therefor, showing my design.

The characteristic feature of the design resides in the combination of the suspension member or support with the cake or body of soap,

substantially as shown in the drawing, and as shown, the suspension member which is of looped formation is of a particular size and proportion with respect to the cake or body of soap. In other words, the twisted suspension member, as regards its length in looped formation, is several times greater in length with respect to the maximum exterior dimension of the cake or body of soap.

I claim:

The ornamental design for a combined cake of soap and support therefor, as shown and described.

LYNDE DE F. HOKERK.
